UNITED STATES PATENT OFFICE.

ELDRIDGE R. JOHNSON, OF MERION, AND JOHN C. ENGLISH, OF PHILADELPHIA, PENNSYLVANIA, ASSIGNEES TO VICTOR TALKING MACHINE COMPANY, A CORPORATION OF NEW JERSEY.

TALKING-MACHINE.

1,217,869.

Specification of Letters Patent. Patented Feb. 27, 1917.

Application filed April 23, 1915. Serial No. 23,299.

To all whom it may concern:

Be it known that we, ELDRIDGE R. JOHNSON and JOHN C. ENGLISH, citizens of the United States, and residents, respectively, 5 of Merion, county of Montgomery, and State of Pennsylvania, and of the city of Philadelphia, county of Philadelphia, and State of Pennsylvania, have invented certain new and useful Improvements in Talking-Machines, of which the following is a specification, reference being had to the accompanying drawings.

Among the principal objects of our invention are to provide a talking machine 15 having amplifying means of relatively great size, and a long, preferably tapering, sound-conveyer interposed between the amplifying means proper and the sound-reproducing means; to provide a talking machine of this character comprising a hollow, 20 preferably tapering, separable sound-conveyer having a minimum number of joints; to provide a talking machine comprising a plurality of separate chambers, respectively 25 housing the actuating mechanism, the major portion of the sound-conveying means, and the amplifying means; to provide a talking machine having sound wave deflecting means whereby the sound waves will be amplified 30 and their tonal qualities improved as they issue from the talking machine; and to provide a talking machine having relatively large, vertically opening amplifying means 35 and a sounding-board, or sound wave deflecting means, so disposed with relation to the mouth of said amplifying means as to deflect the sound waves issuing therefrom toward the front part of the talking machine.

Further objects of our invention are to 40 provide a talking machine of relatively large size having a cabinet which may be readily taken apart by a person unfamiliar with talking machines and without disturbing or disarranging any of the operative parts of the device, for the purpose of more readily moving or transporting the machine, and especially for the purpose of permitting the machine to be readily passed through a 45 door of ordinary width; and to provide a talking machine having a cabinet so constructed as to afford a maximum storage space for records and other accessories, and which shall be of a pleasing and attractive 50 appearance.

Our invention further includes all of the other various novel features of construction and arrangement hereinafter more definitely specified.

In the accompanying drawings, Figure 60 1 is a central, longitudinal, vertical section of a talking machine, constructed in accordance with one form of our invention; Fig. 2 is a top plan view thereof, certain portions being broken away for the sake of 65 clearness; Fig. 3 is a transverse, vertical section thereof, taken on line 3—3 in Fig. 2, looking in the direction of the arrows, certain portions being shown in elevation for the sake of clearness; and Fig. 4 is a fragmentary, transverse, horizontal section taken on line 4—4 in Fig. 3, looking in the direction of the arrows.

Generally speaking our invention may be said to comprise a cabinet having its side 75 walls so arranged that the front portion of the cabinet is of materially less width than the rear portion, the cabinet being transversely separable and provided adjacent the line of separation with a pair of vertically 80 extending partitions arranged one on each side of said line, that portion of the cabinet in front of the partitions serving to house the actuating mechanism of the talking machine and a considerable portion of 85 the sound-conveying means, as well as affording space for the storage of records and other supplies; and that portion of the cabinet in the rear of the partitions serving to 90 form a compartment for the reception of another portion of the sound-conveying means, as well as the relatively large amplifying means, and to support the sound-deflecting means, the cabinet as well as the 95 sound-conveying means being so constructed as to be readily separable adjacent the partitions.

Referring now to the drawings, in which is illustrated one embodiment of our invention, and for convenience of description 100 considering momentarily only that portion thereof in front of the transverse dividing partitions hitherto referred to, the same comprises a cabinet having a suitable frame 1, side walls 2 and 3, bottom 5, top 6, front 105 7, and rear wall or partition 8, the latter forming one of the said dividing partitions when the whole cabinet is assembled. The front of the cabinet is provided with doors 9 and 10, so arranged as to readily give ac- 110

cess to the interior thereof, and the side walls of the cabinet may preferably be formed in curvilinear contour, as best shown in Fig. 2, the major portion of the side walls 5 extending forward from the rear wall 8, of the cabinet for a considerable distance substantially normal thereto, and thereafter being constricted inwardly in a suitable curve or other pleasing configuration as at 10 2' and 3', in such manner that the extreme forward portion of the cabinet will be of considerably less width than the major portion thereof. Suitable apertures may be provided in the side walls, preferably in 15 the rear of the sharply curved portions 2' and 3' thereof, and closed by suitable doors 12 and 13, whereby access may be readily obtained to the interior of the cabinet which may, in the rear of the said doors, be provided with a plurality of suitable horizontal shelves 15 and 16, arranged one above the other, and preferably surrounded and inclosed on three sides by suitable vertical partitions 17 and 18, the sides of the shelves 20 being substantially normal to the general direction to that portion of the side walls in the rear of which the shelves are located. A plurality of other suitable horizontal shelves 20, may also be provided in the rear 25 of the aperture closed by the doors 9 and 10, access to the said shelves being readily obtained by opening the doors, the shelves being also preferably inclosed by suitable vertical partitions 22. For convenience in 30 manufacture the various sets of shelves with their adjacent partitions may be constructed as integral units separate from the cabinet proper, and thereafter secured in position therein by means of suitable fastenings so 35 as to be maintained in permanent fixed relation relatively thereto, and by arranging the various shelves substantially in the manner hereinbefore described, a maximum amount of readily accessible storage space 40 suitable for holding sound records and the like, is obtained without in any manner detracting from the appearance, or tonal qualities of the talking machine.

A suitable aperture 25, in the top 6, of 50 the cabinet affords space for the reception of the motor board 26, suitably supported therein as by the cleats 28, and from which is suspended a suitable motor or other actuating means 30, which may be of any desired 55 or preferred construction, and which may be preferably inclosed in a compartment 32, suitably formed within the cabinet by the partitions 34 and 35, and bottom board 37. The motor may be provided with 60 an upwardly extending shaft 40, passing through a suitable aperture in the motor board, and carrying the rotatable turntable 41, which serves as a support for the sound record 42, in the usual manner. A sound 65 reproducer 45, of any desired or preferred

construction is provided and preferably attached to a U-shaped tube or gooseneck 46, in turn connected with the preferably tapering tone arm 48, extending toward the rear of the cabinet, and supported in such 70 manner as to permit its free horizontal movement, as, for instance, by a suitable bracket 49, and pivot 50, in the well-known manner.

The bracket 49, may preferably be provided with a downwardly extending tubular extension 55, of a length sufficient to extend substantially through the top 6, upon which the bracket is supported by an outwardly extending preferably annular flange 80 57, provided with suitable apertures for the reception of screws 58, which pass through the flange and engage in other suitable preferably internally threaded apertures in a flange 60, formed upon the upper end of the downwardly extending sound-conveyer 65, consisting preferably of a single casting providing a suitable slightly tapering internal passage-way 66. While this portion of the sound-conveyer may be of any desired 85 shape, it is preferably formed so that the upper end thereof will be somewhat forwardly off-set from the lower portion which, adjacent its lowermost extremity, is turned rearwardly through an angle of substantially 90 degrees, and provided with a suitable transversely extending flange 70, for a purpose to be hereinafter described. It will be evident that when the screws 58, are positioned in the flanges 57 and 60, that the upper end of the sound-conveyer will be maintained in rigid relation with the bracket 49, and communication afforded between the interior of the sound-conveyer and the interior of the tone arm 48, whereby 95 the sound waves traveling from the latter will readily pass into the former.

The rear wall or partition 8, of this portion of the cabinet extends between the side walls thereof and from the top of the cabinet to the bottom, and is provided with a suitable aperture 77, for the passage of the sound-conveyer 65. This partition, as well as other of the partitions and walls of the cabinet, may comprise a plurality of suitable relatively thin panels as indicated in the drawings, set in a more rigid surrounding frame work in order to lighten the construction of the cabinet, and in certain instances to produce a more resonant structure; and it will be understood that in the construction of the cabinet generally, the use of such panels and of suitable strengthening braces and cleats in the manner well understood by persons familiar with the 110 art may be resorted to when considered necessary or desirable.

The flange 70, upon the lower end of the sound-conveyer 65, is provided with a plurality of suitable apertures for the recep- 115 120 125 130

tion of the bolts 80, provided with nuts 81, whereby the flange may be secured in fixed relation to the partition 8, and upon the rear side thereof, as clearly shown in Figs. 1 and 4, thus maintaining this portion of the sound-conveyer in rigid operative relation to the front portion of the cabinet, and in a chamber therein separate from the actuating mechanism.

10 Referring now to that portion of the cabinet in the rear of the dividing partitions the same may comprise side walls 85 and 86, rear wall 87, bottom 88, and front wall 89, the side and rear walls being the full height 15 of this portion of the cabinet, which preferably extends somewhat above the top 6, of the front portion. The front wall 89, however, merely extends from above the top 6, sufficiently far to bring its upper extremity into the same horizontal plane as 20 the extremities of the side and rear walls, and is preferably so arranged, by means of a suitable forwardly extending off-set in the side walls, that it will slightly overhang the 25 rear edge of top 6, as clearly shown in Fig. 1. Extending across the front of this portion of the cabinet is the vertical partition 90, corresponding to the partition 8, previously described, the lower portion 92 there- 30 of being preferably formed of relatively thick material, as best shown in Fig. 1, for the purpose of securely supporting another portion of the sound-conveyer, as well as the amplifying means proper. The extreme 35 rear wall 87 may be provided with a suitable opening closed by suitable outwardly opening doors 95 and 96, to afford access to the interior of this portion of the cabinet.

Within the chamber formed in the rear 40 portion of the cabinet is located an upwardly extending portion of the sound-conveyer, together with the amplifying means proper, the former being preferably formed of a single casting 100, and providing front 45 and rear walls 101 and 102, slightly diverging in an upward direction, and side walls 103, also upwardly diverging, but at a considerably greater angle, whereby a sound- 50 conducting passage 105, is formed therein, substantially rectangular in horizontal section and of increasing area toward the upwardly projecting mouth. The lower end 55 of this portion 100, of the sound-conveyer, may, as best shown in Fig. 1, be turned substantially at right angles to the main portion thereof, and provided with a transversely extending flange 110. A suitable aperture 112, is provided in the thickened portion 92 of the partition 90, and through 60 this aperture the sound-conveyer extends and is secured in fixed relation with the partition by means of bolts 114, and nuts 115, which pass through suitable holes in the partition and in the flange 110, in such 65 manner that the flange will abut against the

front side of the partition in opposition to the flange 70, previously described. The flange 110 is also provided with other suitable apertures for the passage of a plurality of screws 120, which engage in other threaded apertures in the flange, 70, and serve to maintain the two flanges face to face when in assembled position, so that the two portions of the sound-conveyer may be rigidly maintained in fixed relation and 75 a continuous passage for the sound waves provided therethrough. The screws 120 may be of sufficient length to pass directly through the partition, as well as the flange, or suitable apertures 122, may be provided 80 in the former for their reception, as best shown in Fig. 4. Of course it will be understood that the heads of the bolts 80 and 114, are countersunk below the surfaces of the respective flanges so that the latter will 85 readily contact over their entire surfaces when in assembled relation.

The sound-conveyer may be provided adjacent its upper extremity or mouth with suitable flanges 130, to which the side walls 90 131, and end walls 132, of the upwardly extending amplifier 135, are secured, as by the screws or rivets 136, the walls terminating preferably adjacent the top of, but out 95 of contact with, the cabinet.

The amplifier may also preferably be provided with a plurality of transverse partitions 138, either extending vertically upward therein or diverging, more or less depending upon the number and style of partitions used, and these partitions as well as the side and end walls of the amplifier may 100 preferably be formed of wood or other resonant material, either of constant thickness, or tapered upwardly, as shown in connection 105 with the side walls 131, in Fig. 3. If desired, however, any other form or type of amplifier may be employed, the same being preferably supported solely by the upwardly turned sound-conveyer, and having no connection whatsoever to any portion of the cabinet.

For the purpose of closing the open upper end of the rear portion of the cabinet, a lid 150, preferably having a depression or hollow 115 151, in its under side, may be provided and hinged, as by hinge 152, to the cabinet adjacent its rear edge, and a sounding-board or sound-deflector 153, consisting preferably of a thin sheet of wood or other resonant material may extend across the depression in the lid in such manner as to 120 cover the entire under side of the latter. This sound-deflector or sounding-board may be of either constant thickness or else may be tapered from back to front or vice versa, as may be desired, and may preferably be secured in fixed relation with the lid. A suitable link 155, or other preferred means 125 serves to hold the lid in raised position while 130

the machine is in operation in such manner that the sounding-board 153, is maintained in angular relation with the open mouth of the amplifier, whereby the sound waves issuing therefrom and impinging against the sounding-board, are thereby deflected from their initial upward direction forwardly toward the front part of the machine and simultaneously improved in tonal quality. 5 When the machine is not in operation, or it is desired to greatly muffle the reproduction, the lid may be lowered by suitable manipulation of the link and of a catch 156, by which the position of the lid may be controlled.

10 For the purpose of covering the turntable and sound-reproducing mechanism, as well as of affording a more artistic finish to the cabinet, another lid 160, hinged at 161, is provided and designed to close against a suitable frame 165, secured to the top 6, of the forward portion of the cabinet, and surrounding those portions of the mechanism which project above the top. This lid may 20 be maintained in raised position when desired by means of a suitable link 168, in the well-known manner.

15 A plurality of feet or legs 200, for the purpose of supporting the cabinet are provided and arranged at suitable points, and in practice it is desirable to provide one or more legs 201 and 202, located substantially along the median line of the cabinet and respectively beneath the front and rear portions thereof, for the purpose of affording a support to the sections of the cabinet when the latter is dis-assembled, as hereinafter described.

20 For the purpose of securing the front and rear portions of the cabinet in assembled relation, a plurality of rearwardly extending and suitably spaced bolts 170, are provided and so arranged that their forward ends are fixedly secured within the partition 8, 25 from which point the bolts extend rearwardly for a sufficient distance to pass completely through the partition 90, or its thickened portion 92, as the case may be, when the cabinet is assembled, and afford space 30 for the reception of the washers 171, and thumb nuts 172, upon their ends, which are suitably threaded for the reception of the latter, and for the purpose of maintaining the two partitions 8 and 90, in correctly 35 spaced relation, vertically extending strips 176, secured to the partition 8 may be provided adjacent the bolts 170, and through which the latter preferably extend. If desired, a washer 180, of felt or other resilient 40 material, may surround each bolt between the rear faces of the strips and the adjacent face of the partition 90.

45 It will thus be evident that, when the two portions of the cabinet are moved into operative relation, as shown in the drawings,

the bolts 170 will extend through the partition 90, or its thickened portion 92, as the case may be, and that by placing the thumb nuts 172 upon the ends of the bolts and tightening them down against the washers 171, the two portions of the cabinet may be rigidly secured together to form a unitary operative structure, the two portions of the sound-conveyer being similarly maintained in fixed relation by means of the screws 120 5 passed through the abutting flanges 70 and 110.

60 It will furthermore be evident that the front and rear portions of the cabinet may be readily separated when desired merely by 80 removing the thumb nuts 172, washers 171, and screws 120, which operation may be readily accomplished when the doors 95 and 96, at the rear of the cabinet are opened, thus permitting the rear portion of the cabinet to be moved away from the front portion, to, separate the machine into two self-contained and independent units, which may be easily transported and readily passed through a door of ordinary width, an operation which, owing to the relatively large size of the machine, would be impossible when the same is assembled for use. Furthermore, such separation of the two portions of the machine may be readily effected 95 by a person entirely unfamiliar with talking machines, as it is accomplished without any interference whatsoever with the delicate operative parts of the device, and without even disturbing the records or other accessories within the storage spaces in the interior of the cabinet.

65 It will thus appear that we have provided a talking machine having amplifying and sound-conveying means of relatively large 105 size, which is of pleasing appearance, and which comprises numerous novel features of construction and arrangement. Furthermore, owing possibly to the relatively large dimensions of the amplifier and the isolation 110 of certain parts of the device in separate chambers, it has been found in practice that the reproduction of sound by a machine embodying the characteristics of our invention is extremely life-like and without disagreeable features, while being of great volume, so that a machine constructed in accordance with our invention is especially suitable, among other purposes, for reproducing sound in auditoriums and similar 115 rooms of large size, and yet capable of ready transportation from place to place as may be required.

70 While we have described with considerable detail one embodiment of our invention, 125 we do not desire to limit ourselves to the exact details of construction and arrangement thereof as herein set forth, as it will be evident that various changes may be made in the form and location of the various parts 130

of the device, and in numerous other details relative to the construction and arrangement thereof without departing from the spirit and scope of the invention as defined in the 5 appended claims.

Having thus described our invention what we claim and desire to protect by Letters Patent of the United States is:

1. In a talking machine, the combination 10 of a cabinet having front compartments and a rear compartment, a top, a partition separating said front and rear compartments, of actuating means in one of said front compartments below said top, sound-reproducing means above said top, sound-conveying means extending through said top and through the other of said front compartments and through said partition, an upwardly projecting sound-amplifier in said 15 rear compartment, in operative communication with said sound conveying means and having its mouth adjacent the top of said rear compartment, a movable lid above said rear compartment, a movable cover inclosing 20 said sound-reproducing means, and means operative to permit the separation adjacent said partition of that portion of the cabinet comprising the rear compartment from that portion thereof comprising 25 the front compartments.
2. A talking machine comprising a cabinet having a plurality of vertically extending transverse partitions and having a plurality of separate compartments on one side 30 of said partitions and a single compartment on the other side of said partitions, actuating mechanism in one of said first-mentioned compartments, sound-conveying means in another of said first-mentioned 35 compartments and extending into said single compartment through said partitions,
- sound-amplifying means in said single compartment supported by said sound-conveying means, and means whereby that portion of said cabinet containing said actuating mechanism may be separated from that portion of said cabinet containing said sound-amplifying means on a plane extending between 40 said partitions, and means whereby said sound-conveying means may be similarly separated.
3. In a talking machine, the combination 45 of a cabinet sub-divided by a partition, sound reproducing means and sound amplifying means carried by said cabinet on opposite sides of said partition, and sound conveying means extending on both sides of said partition and connecting said reproducing means and said amplifying means, said cabinet and said conveying means being 50 each formed of separable sections united adjacent said partition.
4. In a talking machine, the combination 55 of two separable units, means to rigidly secure said units together, a sound reproducing mechanism and a motor mechanism within one of said units, a lid on the top of said unit to inclose and give access to said sound reproducing mechanism, an amplifier in the other of said units arranged to discharge sound upwardly, a lid on the top of said last mentioned unit arranged when raised to form a deflector to direct the sound from said amplifier over said first mentioned unit, and a sound conveyer extending within said 60 units and connecting said sound reproducing means with said amplifier.

In witness whereof, we have hereunto set our hands these 13th and 21st days of April, 1915.

ELDRIDGE R. JOHNSON.
JOHN C. ENGLISH.
